CLAIM

What is claimed is the ornamental design for a cosmetic product, as shown and described.

DESCRIPTION

FIG. 1 is a perspective view of a cosmetic product, as disposed in a container, showing my new design from the top and front thereof, the dotted lines depicting environmental subject matter only and forming no part of the claimed design;

FIG. 2 is a top plan view of the cosmetic product of FIG. 1;

FIG. 3 is a bottom plan view of the cosmetic product of FIG. 1;

FIG. 4 is a front elevational view of the cosmetic product of FIG. 1;

FIG. 5 is a right side elevational view of the cosmetic product of FIG. 1;

FIG. 6 is a rear elevational view of the cosmetic product of FIG. 1;

FIG. 7 is a left side elevational view of the cosmetic product of FIG. 1;

FIG. 8 is a perspective view of a cosmetic product, as disposed in an alternative container, showing my new design from the top and front thereof, the dotted lines depicting environmental subject matter only and forming no part of the claimed design;

FIG. 9 is a top plan view of the cosmetic product of FIG. 8;

FIG. 10 is a bottom plan view of the cosmetic product of FIG. 8;

FIG. 11 is a front elevational view of the cosmetic product of FIG. 8;

FIG. 12 is a right side elevational view of the cosmetic product of FIG. 8;

FIG. 13 is a rear elevational view of the cosmetic product of FIG. 8; and,

FIG. 14 is a left side elevational view of the cosmetic product of FIG. 8.
